UNITED STATES PATENT OFFICE

169,288

WALL SWITCH PLATE

George F. Russell, Sherman Oaks, Calif., assignor to Robert Schwarz, Jr., and William H. Gottschalk, doing business as Falcon Plastic Products Mfg. Co., Culver City, Calif., a copartnership

Application October 4, 1952, Serial No. 21,692

Term of patent 14 years

(Cl. D26—13)

To all whom it may concern:

Be it known that I, George F. Russell, a citizen of the United States of America, residing at Sherman Oaks, county of Los Angeles, State of California, have invented a new, original and ornamental Design for a Wall Switch Plate, of which the following is a specification, reference being had to the accompanying drawing forming a part thereof.

Figure 1 is a front view of my wall switch plate, showing my new design.

Figure 2 is a side edge view thereof.

Figure 3 is a top edge view thereof.

I claim:

The ornamental design for a wall switch plate, substantially as shown.

GEORGE F. RUSSELL.
